PORTABLE GRILL

Ralph E. Brooks, Albion, Mich.

Application August 14, 1958, Serial No. 52,202

Term of patent 3½ years

(Cl. D81—10)

Fig. 3.

I claim:

The ornamental design for a portable grill, substantially as shown.
